GRAPHIC RECORDER

Edward W. Vopat, Redwood City, and Ralph Herzog,
Mountain View, Calif., assignors to Varian Associates,
Palo Alto, Calif., a corporation of California

Filed Aug. 16, 1963, Ser. No. 76,242

Term of patent 14 years

(Cl. D26—14)

FIG. 1

FIG. 2

FIG. 3

FIG. 4

FIG. 5

FIG. 1 is a perspective view of a graphic recorder, showing our new design;

FIG. 2 is a top plan view, to an enlarged scale;

FIG. 3 is a front elevational view, to an enlarged scale;

FIG. 4 is a side elevational view, to an enlarged scale, the opposite side being substantially a mirror image; and

FIG. 5 is a back elevational view thereof, to an enlarged scale.

Portions of FIGS. 1 and 3 are diagonally lined to indicate transparency.

The dominant features of the design reside in the portions shown in full lines.

We claim:

The ornamental design for a graphic recorder as shown and described.
